LOCOMOTIVE

Ralph W. Anderson, Wauwatosa, Wis.

Application September 13, 1933, Serial No. 689,182

10 Claims. (Cl. 110—122)

The invention relates to improvements in locomotives, and particularly to the smoke-box and spark arrester thereof.

The prevention of fires due to the escape from locomotives of hot sparks has been a serious problem. One safeguard in common use is a heavy wire screen across the smoke-box for preventing the escape of sparks, or so reducing them in size that they lose their dangerous character before coming in contact with any inflammable material. This expedient has been quite inefficient and unsatisfactory.

The objects of the present invention are to insure the deadening of the sparks before their escape from the smoke stack by prolonging their passage through the smoke-box and so reducing their size by attrition that they will readily cool as they escape from the locomotive.

A further object is to insure the discharge of substantially all of the sparks or cinders from the smoke-box, thereby avoiding the necessity of frequent cleaning of the smoke-box.

While the invention may be variously embodied, a form of construction is hereinafter described, and is illustrated in the accompanying drawings, which has proved to be highly efficient.

In the drawings:

Fig. 1 is a detail longitudinal vertical section through the front end of a locomotive equipped with the improved spark arrester;

Fig. 2 is a sectional view on the line 2—2 of Fig. 1, with parts broken away;

Fig. 3 is a detail vertical section through the spark arrester and portions of the locomotive; and

Fig. 4 is a sectional view on the broken line 4—4 of Fig. 3.

The invention is shown as applied to a locomotive already in service. The front end ring of the locomotive is shown at 10; its smoke stack at 11; its front flue sheet at 12; superheater pipes 13 leading to a header; a portion of a steam pipe leading to the engine cylinders at 14; and the exhaust nozzle leading from the cylinders at 15.

The spark arrester proper comprises a pair of casings 16, 17, the former inclosing the latter and being of substantially greater diameter. Both casings may be formed of sheet metal, and each takes the form of a pair of truncated cones with their bases adjacent.

The two sections 18, 19, of the outer casing abut, while the two sections 20, 21, of the inner casing 17 are spaced apart. The outer casing 16 is open at its top and bottom. The inner casing

17 is closed to the smoke-box at the top and bottom but is laterally open.

The lower end of the section 21 of the inner casing 17 rests upon and is secured to the table plate 22 of the smoke-box of the locomotive and incloses the exhaust nozzle 15. The upper section 20 of the inner casing surrounds the petticoat 23 of the smoke stack 11 and fits snugly thereupon. The outer casing 16 is spaced from the table plate of the smoke-box and is supported by legs 24 bolted thereto.

A series of vertical baffle and deflecting plates 25, annularly disposed between the upper and lower sections 20, 21, of the casing 17, are welded to both of these sections and, at their upper and inner corners, to a ring 26. Each of these plates 25 extends inwardly from the outer margin of the inner casing and is set in a plane slightly oblique to the radius thereof, passing through its outer margin.

One face 27 of each of these plates is roughened, and the plates are so set that material entering the inner casing 17 obliquely in one general direction will be deflected toward the center of the casing and into the column of exhaust steam issuing from the nozzle 15.

Two sets 28, 29, of spirally disposed guide vanes are located between the outer and inner casings, the one set 28 occupying the upper half of the arrester and the other, 29, the lower half. All of these vanes extend from a margin, either top or bottom, of the arrester and in the same circumferential direction.

The front wall 30 of the smoke-box is preferably located but a short distance in advance of the spark arrester, and in new locomotives may constitute the front end wall. The table plate 22 is extended back and inclined downwardly to the bottom of the front flue sheet 12, as shown at 31, and prevents an accumulation of cinders in the bottom of the box.

The efficiency of the spark arrester has been found to depend, to some extent, upon the positioning of the lower end of the petticoat 23, and may vary in different locomotives and under differing conditions, such as a change in the grade of fuel being used. It therefore becomes desirable to provide for the adjustment of the petticoat. As shown, this part of the smoke stack telescopes into the upper fixed section 11, and is supported on arms 32, projecting upwardly from and rigidly attached to the upper section 20 of the inner casing 17. Brackets 33, attached to the petticoat, are bolted to these arms, and the latter are provided with a longitudinal series of apertures, as

shown in Fig. 2, to permit of the vertical adjustment.

Smoke entering the smoke-box is forced, or drawn into the spark arrester, entering the outer casing at both its top and bottom, being guided by the vanes 28 and 29 to the lateral opening in the inner casing, where the ascending and descending currents each arrests the other and the smoke is impelled against the roughened faces 27 of the baffle plates 25, and is by them guided directly to the ascending column of exhaust steam. In passing from the flue openings through the sheet 12 to the stack there is, of course, violent agitation, resulting in the reduction of the sparks carried by the smoke both by attrition and impact. These solid particles are violently thrown against the rough surfaces of the plates 25, and such of them as are of any substantial size are thereby broken up.

20 The passage of smoke through the box and arrester occupies sufficient time to permit the sparks to lose considerable of their heat, and by reason of their fine subdivision their temperature is so low as they issue from the stack that all 25 danger of the starting of fires is avoided.

The roughening of the plates 25 may be accomplished in any desired manner. In practice it has been found quite satisfactory to secure it by attaching, as by welding, to the face of the 30 plates a piece of rather coarse reticulated screen.

While the form of construction shown and described is found to be highly efficient, various changes therein may be made within the scope of the invention as defined in the appended 35 claims.

I claim as my invention—

1. In a steam locomotive having a smoke-box, a smoke stack leading therefrom and an exhaust nozzle discharging thereto, the combination of a 40 spark arrester comprising an inner and an outer casing, the inner casing fitting upon the nozzle and stack and being laterally open adjacent its median zone and open at the bottom to the nozzle and at the top to the stack, the outer casing 45 being open at the top and bottom, spirally arranged vanes interposed between the two casings and leading from the top and bottom of the outer casing to the lateral opening of the inner casing, and an annularly arranged series of vertical baffle plates within the inner casing and crossing its lateral opening and positioned to deflect material entering such opening toward the center of the casing.

2. In a steam locomotive having a furnace 55 boiler and engine, a smoke-box, a smoke stack leading therefrom and an exhaust nozzle discharging thereto, the combination therewith of a spark arrester fitting upon the adjacent ends of the stack and nozzle and comprising an 60 outer and inner casing, the outer casing being open at top and bottom, the inner casing being laterally open adjacent its median zone, spirally arranged vanes interposed between the two casings and leading from the top and bottom of the outer 65 casing to the lateral opening in the inner casing, and an annularly arranged series of vertical baffle plates within the inner casing and crossing its lateral opening and positioned to deflect material entering such opening toward the axis of the 70 casing, the deflecting faces of such plates being roughened.

3. A spark arrester comprising a pair of concentrically related casings for inclosing the lower end of the smoke stack and the exhaust nozzle 75 of a locomotive, the outer casing being open at

the top and bottom and the inner casing open circumferentially only, means for guiding material entering the outer casing to the opening of the inner casing, and means within the latter for directing toward its axis material entering its 5 opening.

4. A spark arrester comprising a pair of concentrically related casings for inclosing the lower end of the smoke stack of a locomotive and the exhaust nozzle thereof, both casings having the 10 form of a pair of truncated cones having their bases adjacent, the outer casing being open at its ends only and the inner one being open circumferentially only, means for guiding material entering the outer casing to the opening of the 15 inner casing, and means within the latter for directing toward its axis material entering its opening.

5. A spark arrester for locomotives having a 20 vertical smoke stack and an exhaust nozzle discharging thereto, such arrester comprising a pair of casings, one within the other and enclosing the nozzle and the lower end of the stack, the inner casing being closed at the top and bottom and laterally open and the outer casing being 25 open at the top and bottom, spirally arranged vanes between the two casings and leading to the lateral opening, and an annular series of vertical baffle plates within the inner casing for deflecting entering material to the center thereof. 30

6. In a locomotive, in combination, a smoke-box having a table plate, a vertical smoke stack, an exhaust nozzle discharging into the stack, a spark arrester comprising a laterally open casing secured to the table plate and inclosing the nozzle 35 and the lower end of the stack, such stack end being adjustably carried by the casing, and means for directing products of combustion into the lateral opening of the casing.

7. In a locomotive having a smoke-box, an exhaust nozzle discharging thereto and a smoke stack leading therefrom, the combination with such elements of a spark arrester comprising a casing in the form of an inverted truncated cone rising from and enclosing the nozzle and discharging into the stack, an outer casing open at the bottom and being of like form and concentric with the first-named casing and communicating with the chamber thereof at the upper end of the latter, spirally disposed vanes between the 50 two casings and means for arresting the ascent of currents between the casings at the level of such means of communication.

8. In a locomotive having a smoke-box, an exhaust nozzle discharging thereto and a smoke 55 stack leading therefrom, the combination with such elements of a spark arrester comprising a casing in the form of an inverted truncated cone rising from and enclosing the nozzle and discharging into the stack, an outer casing open at 60 the bottom and being of like form and concentric with the first-named casing and extending above the latter, spirally disposed vanes between the two casings, an annular series of baffle plates leading upwardly from the inner casing and positioned to guide currents entering between them toward the axis of such casing and means for arresting the ascent of currents entering between the casing approximately at the top of the outer 65 casing. 70

9. In a locomotive having a smoke-box, an exhaust nozzle discharging thereto and a smoke stack leading therefrom, the combination with such elements of a spark arrester comprising a casing in the form of an inverted truncated cone 75

rising from and enclosing the nozzle and discharging into the stack, an outer casing open at the bottom and being of like form and concentric with the first-named casing and extending above the latter, spirally disposed vanes between the two casings, an annular series of baffle plates lead-in upwardly from the inner casing and positioned to guide currents entering between them toward the axis of such casing, the guiding faces of the plates being roughened and means for arresting the ascent of currents entering between the casings approximately at the top of the outer casing.

10. In a locomotive having a smoke-box, a smoke stack leading therefrom and an exhaust nozzle discharging therewith, the combination with such elements of a spark arrester in line

with and open to the nozzle and comprising a pair of concentric casing elements each in the form of a truncated cone, the inner element snugly inclosing the stack and the outer element being open at the top and extending below the inner element, a series of spirally disposed vanes between the two casing elements and extending below the inner one, means for arresting currents descending between the vanes, an annular series of vertical baffle plates within and extending below the inner casing element and positioned to guide currents entering between them toward the axis of such element, the guiding faces of the plates being roughened.
